[57] CLAIM

The ornamental design for a fishing lure, as described and shown.

DESCRIPTION

FIG. 1 is a view in perspective from the front and above the fishing lure of my new design;
FIG. 2 is a side view of the fishing lure, the view from the other side being a mirror image; and
FIGS. 3, 4, 5 and 6 are top, front, rear and bottom views respectively.

FIG. 1

FIG. 3

FIG. 4

FIG. 2

FIG. 5

FIG. 6
